UNITED STATES PATENT OFFICE.

ALBERT J. LEWIS, OF PORT ARTHUR, TEXAS.

ANTIRATTLER FOR WINDOWS.

Application filed March 7, 1923. Serial No. 623,433.

To all whom it may concern:

Be it known that ALBERT J. LEWIS, a citizen of the United States of America, residing at Port Arthur, in the county of Jefferson and State of Texas, has invented certain new and useful Improvements in Antirattlers for Windows, of which the following is a specification.

The present invention relates to anti-rattler for windows of dwellings and vehicles and is primarily designed to produce a device which will be automatic in its nature.

One of the principal features resides in a construction which may be formed from a single strip of wire and which at the same time includes an attaching means for the device.

Another feature resides in a construction, the tension of the anti-friction roller of which on the window sash may be readily varied.

Other features reside in the extreme simplicity of the arrangement and in the particular construction and operation of the device.

In the accompanying drawings,

Figure 1 is a front view of a window showing the application of my anti-rattler thereto.

Figure 2 is a side elevation of the anti-rattler complete,

Figure 3 is an end elevation of the device shown in Figure 2 and at right angles thereto, and

Figure 4 is an enlarged fragmentary view of a window, showing the device as applied and

Figure 5 is a side view of the device modified as to its attaching means.

Referring now more particularly to the drawings by numerals of reference, 2 indicates the frame of a window, 4 and 6 respectively the upper and lower slidable window sash and 8 the usual guide-stops therefor, and while the anti-rattler, hereinafter described is especially useful in connection with the windows of dwellings, it may be applied to the windows of vehicles with equal advantages.

The anti-rattler comprises a spring wire strip 10, bent intermediate its ends to form a multiple coil torsion spring 11, the axis of which is arranged at right angles to the axis of the oppositely disposed arms 12 and 14.

The arm 12 is bent at its outer end at sub-

stantially right angles to provide a laterally extending prong 16, the axis of which is substantially parallel with that of the axis of the coil spring 11, said prong being 60 adapted to be driven into the side of the guide stop 8.

The outer end of the arms 14, is also bent similarly to the prong 16 to provide a bearing spindle 18 for an anti-friction roller 20, adapted to be yieldingly held in engagement with the window sash through the tension of the coil spring 11.

The coil 11 is adapted to receive a pin or nail 22, which passes axially therethrough, 70 and into the sash guide 8, said pin serving as the pivot or fulcrum upon which the roller supporting arm swings.

As shown in Figure 2, the arms 12 and 14 are arranged at an angle of substantially 45 75 degrees so that the roller, 20, will be offset inwardly from the vertical plane of the upper arm 12, and will engage the window sash with the proper degree, of pressure. This degree of pressure may of course be 80 varied by changing the angular relation of the arms 12 and 14.

If preferred in lieu of the attaching prong 16, I may form the end of the arm 12 into an eye, the axis of which will lie in a 85 plane parallel with that of the axis of the coil spring.

Further, it is to be understood that the anti-rattler will necessarily be made both 90 right and left hand for attachment to opposite sides of the window.

From the foregoing description of the construction of my improved apparatus, it will be seen that I have provided a simple, inexpensive and efficient means for carrying 95 out the objects of the invention, and while I have particularly described the elements best adapted to perform the functions set forth, it is obvious that various changes in form, proportion and in the minor details of construction may be resorted to without departing from the spirit or sacrificing any of the principles of the invention.

What I claim as new and desire to protect by Letters Patent is:

In combination with a window frame, a vertically slidable sash therein, and a guide strip for said sash; an anti-rattling device for the sash comprising a single strand of resilient wire convoluted intermediate its ends 110 to form a coil, the wire continuing from the terminal coils of said convolutions being ex-

tended to form a pair of oppositely projected arms, the ends of said arms being bent at right angles in the same direction, one of said angular bent ends being tapered to form an engaging point adapted for introduction in the outer side face of said guide strip, a pin having an enlarged head at one end thereof extended through said convolutions and engaged with the outer face of said guide strip in a vertical plane forward of the vertical plane of the engagement of

the aforesaid bent end of the one arm, said pin serving as a fulcrum point for the convoluted portion of the wire and the head thereof serving to prevent the convolutions from being distorted laterally, and a roller journaled on the angular bent end of the opposite arm of the wire disposed in frictional contact with the front face of the frame of the slideable sash, as and for the purposes described. 15

ALBERT J. LEWIS.
